L. J. BETTS

TRAFFIC SIGN

Filed April 6, 1925

Inventor

Louis J. Betts

By

Dennis L. Morris

Attorney

UNITED STATES PATENT OFFICE.

LOUIS J. BETTS, OF WARREN, PENNSYLVANIA.

TRAFFIC SIGN.

Application filed April 6, 1925. Serial No. 21,195.

This invention relates to traffic signs and particularly to that type of sign which is adapted to be semi-permanently located, it being one of the objects of the invention to provide a sign so constructed as to be readily attachable to its anchor block, and which when in place covers and protects its attaching means so that the sign cannot be unauthorizedly removed, while at the same time being readily detachable by one in possession of a special key.

Another object of the invention is to provide a traffic sign, the legend-bearing portion of which can be removed so as to be interchangeable with other legend-bearing portions having insignia of different purport, said portions being characterized by the provision of securing means which can not be detached by one who is not provided with a tool designed especially for that purpose.

Other objects of the invention relate to specific features thereof, and will appear as the following description of an illustrative embodiment of the invention proceeds.

In the drawings:

Figure 1 is a front elevation, partly in section, illustrating my improved traffic sign.

Figure 2 is a vertical section of the anchoring block, the base, the spacer and the lower end of the standard at a right angle to Figure 1.

Figure 3 is an underneath plan view of the base of the traffic sign.

Figure 4 is a plan view of the anchor block.

Figure 5 is a section taken along the line 5-5 of Figure 1.

Figure 6 is a section through the shield which protects the set-screw shown in Figure 5.

Figure 7 is a side elevation of the legend-bearing portion of the sign.

Referring now in detail to the several Figures, the numeral 1 represents a base which is preferably made from cast iron and provided on its upper side with an annular flange 2 forming a socket. A standard 3 is supported in said socket, said standard being preferably made from a piece of pipe tubing, and of suitable length to carry the legend-bearing portion of the sign at an appropriate height.

The base is secured to the ground by the anchoring bolt 4, which extends head downwardly through a hole in said base, and en-

gages the anchor block 5. Said anchor block is preferably of the type described in my Patent #1,469,146 granted September 25, 1923, and consists of a webbed portion 6 adapted to be embedded in concrete, the upper face of said block being provided with means interlocking with the head 7 of the bolt 4.

Said means consists of a key-hole slot 8 opening in the upper surface of the anchor block, having an enlarged end capable of receiving the head 7 of the bolt 4, and a narrow portion of sufficient width just to admit said shank of the bolt. The narrow portion 70 is undercut forming a recess into which the head of the bolt may slide, and such undercut portion forms a flange which overhangs the bolt head and prevents its escape from the anchor block by movement in a direction 75 axially of said bolt.

The upper or free end of the bolt 4 is formed with threads, and preferably passes through a spacer 9, a retaining nut 10 being screwed upon the threaded end of said bolt 80 above the spacer. The latter is preferably made at least as tall as the flange 2 which forms the socket, the object of said spacer being to keep the nut above the end of the socket so that it may be conveniently accessible for the application of a wrench.

When the base 1 is in place as shown in Figure 1, but before the standard has been introduced into the socket, the nut 10 may be tightened against the upper end of the spacer 9 so as to draw the head 7 of the bolt 4 tightly against the overhanging flange 11 of the anchor block. This secures the base in position. The base is formed on its lower face with a key or plug 12 which fits 90 into the enlarged part of the key-hole slot 8 when the bolt-head is in the recess beneath the narrow part of said slot. When the nut 10 is screwed on the threaded portion of the bolt 4 against the upper end of the spacer, as described, it draws the key 12 into the enlarged part of the key-hole slot 8 so that the bolt-head 7 cannot thereafter escape through sidewise shifting of the base of the traffic sign. The bolt is made of such length 95 that the nut 10 can be backed off a considerable distance in order to permit the base to be tilted until the key 12 is out of the enlarged part of the keyhole slot. The base can then be shifted sidewise in a direction 100 which will bring the bolt-head 7 into registry with the enlarged part of the key-hole

slot 8, whereupon the entire base may be lifted from the anchor block. The upper surface of the anchor block is preferably flush with the surface of the street, so that said block offers no impediment to traffic after the traffic sign has been removed therefrom.

In erecting the traffic sign, the standard 3 is placed in position after the base has been 10 secured to the anchor block in the manner above described, and telescopes over the nut 10 fully covering and protecting the latter. A set screw 13 screws into an aperture in the side of the flange 2 and engages the standard 15, locking the latter in place. When said set screw is in place its head preferably terminates flush with the surface of the flange 2 and is formed with an internal polygonally shaped recess which is fitted only by a special 20 wrench 14, presumed to be carried by an authorized party. By virtue of the construction just described the standard cannot be removed from the base by ordinary tools, and, with the standard 3 in place the nut 10 25 cannot be tampered with. This makes the standard and base secure against unauthorized removal.

The spacer 9 is preferably formed with a flange 15 at its lower end upon which the 30 lower end of the standard 3 rests. By loosening the set screw, the standard 3 may be oriented so as to face the legend-bearing portion of the sign in any desired direction, the flange 15 acting as an end bearing for said standard. Said flange also serves to lift out any accumulation of dirt which may collect 35 in the socket.

The legend-bearing portion of the sign may be of any desired form, it being here 40 shown as a flat circular plate 16 upon which suitable insignia may be cast integrally therewith, painted thereupon, or applied thereto in any desired manner. The plate 16 is preferably provided with a shank 17 45 telescopically fitted within the upper end of the standard 3. Said shank is formed with a passage 18 into which suitable securing means may be introduced. Said securing means in the present instance is shown as 50 consisting of a screw 19 extending through an aligned aperture in the side of the standard and screwing into the passage 18. Said screw preferably has a polygonal recess in its head of the same size and shape as that in the set screw 13, so that the same wrench may 55 be used in manipulating both screws.

The standard being of commercial drawn or welded tubing, there are no projections or lugs on the same in which the head of the 60 screw 19 might be imbedded. Therefore I provide a protector or shield 20 having a recess 21 in which the head of the set screw is housed, and a passage 22 between said recess

and the back face of the shield, said back face being convex to match the curvature of the standard. The shield is positioned upon the set screw before the latter is put in place and, when the set screw is tightened to final position, the convex face of the shield hugs the standard so that the shield cannot be 70 turned even by the application of pliers thereto. It therefore becomes impossible to remove the set screw except by use of the special wrench provided for the purpose and the legend-bearing portion of the sign is 75 consequently safeguarded against removal by one without the authority to do so.

While I have described what I believe to be a practical and efficient embodiment of my invention it is to be understood that various changes in the structure and disposition of the several parts may be made without departing from the scope of the invention as defined in the appended claims.

Having described my invention what I 85 claim as new and desire to secure by Letters Patent, is:—

1. In a sign support, a base having an annular flange forming a socket, a spacer in 90 said socket extending upward substantially to the level of the top of said flange, anchoring means passing loosely through said base and spacer having the lower end thereof adapted to engage an anchor block, and having the upper end thereof projecting through said spacer, securing means carried by said anchoring means and engaging the upper end of said spacer for bringing said base into fixed relation to said anchor block, a standard 95 telescopically arranged with respect to said flange and surrounding said securing means, and means carried by said flange for locking said standard to said base.

2. In a sign support, a base having an annular flange forming a socket, a spacer within 100 said socket having an outwardly extending flange at its lower end, said spacer extending upwardly substantially to the level of the top of said flange, anchoring means passing loosely through said base and spacer having the lower end thereof adapted to engage an anchor block and having the upper end projecting through said spacer, securing means carried by said anchoring means and engageable with the upper end of said spacer for bringing said base into fixed relation 105 with said anchor block, a standard telescopically arranged with respect to said socket and seated upon the flange of said spacer, said standard surrounding said securing means, and means carried by said flange for locking said standard to said base.

In testimony whereof I have hereunto set my hand.

LOUIS J. BETTS.
